UNITED STATES PATENT OFFICE.

PAUL PIGNOT, OF YONKERS, NEW YORK, ASSIGNOR TO ALEXANDER SMITH & SONS CARPET COMPANY, OF SAME PLACE.

DESIGN FOR A CARPET.

SPECIFICATION forming part of Design No. 14,037, dated July 3, 1883.

Application filed May 4, 1883. Term of patent 3½ years.

To all whom it may concern:

Be it known that I, PAUL PIGNOT, of Yonkers, Westchester county, New York, have invented a new and original Design for Carpets, 5 of which the following is a specification.

The accompanying photograph illustrates my new design for carpets.

This invention relates to a new design for carpets, oil-cloths, and analogous fabrics; and 10 it consists of the new ornamentation of parts hereinafter more fully pointed out.

In the accompanying photograph, the letter A represents a spray of flowers, from which project, and beneath which are placed, in sundry 15 directions, fern-like leaves a, the background of said fern-like leaves with reference to the floral spray A being so arranged as to pro-

duce an effect similar to that of a spray of flowers appearing on the foliage of a tree fully covered with leaves. From this groundwork of 20 leaves extends, without any apparent connection with the other flowers, a small spray, b, of flowers, which serves to heighten the effect that is produced by the arrangement of the main spray A and the leaves a. 25

I claim—

The design for carpets, consisting of the spray A, leaves a, and spray b, substantially as shown.

PAUL PIGNOT.
